U.S. Cl. D87—8

FIG. 1 is a top plan view of a key case, showing our new design;

FIG. 2 is a side elevational view;

FIG. 3 is an end view; and

FIG. 4 is a plan view on a reduced scale, showing the key case in an open position.

FIG. 5 is a section taken substantially on line 5—5 of FIG. 4 showing the inner partitions which form the key retaining pockets.

The bottom plan view of the key case is substantially a mirror image of the top plan view shown in FIG. 1.

We claim:

The ornamental design for a key case, as shown and described.
